ELECTRICAL MASSAGER FOR THE FACE

Samuel L. McNair, Whitman, and Mary Florence Stead,
Saugus, Mass.

Application April 9, 1959, Serial No. 55,419

Term of patent 14 years

(Cl. D83—1)

Fig. 1 is a top plan view of an electrical massager for the face embodying our new design;

Fig. 2 is a side elevational view;

Fig. 3 is a rear end elevational view;

Fig. 4 is a front end elevational view; and

Fig. 5 is a sectional view showing the corrugated gripping surface of the handle thereof.

We claim:

The ornamental design for an electrical massager for the face, substantially as shown.
